UNITED STATES PATENT OFFICE.

PERCY LIONEL DAVIS, OF SAN FRANCISCO, CALIFORNIA.

DISPLAY-STAND.

1,072,704.

Specification of Letters Patent.

Patented Sept. 9, 1913.

Application filed December 21, 1912. Serial No. 738,059.

To all whom it may concern:

Be it known that I, PERCY L. DAVIS, a citizen of the United States, residing at San Francisco, in the county of San Francisco and State of California, have invented 5 certain new and useful Improvements in Display-Stands, of which the following is a specification.

This invention relates to display stands 10 such as are used in stores for exhibiting to advantage articles of merchandise.

The objects of the invention are to provide a stand of this nature which shall be ornamental in appearance, efficient and convenient 15 in use, and cheap to construct.

The invention further seeks to provide a display stand which can be readily packed into small compass for shipment or storage.

With the above objects in view the invention 20 consists in the construction and arrangement of parts hereinafter described, and illustrated in the accompanying drawings, in which:—

Figure 1 is a front elevation of my improved display stand as it appears when in use. Fig. 2 is a view of the device showing the parts separated and folded to facilitate packing. Fig. 3 is a detailed view of one of 25 the clips which I preferably employ to hold the articles to be displayed, and Fig. 4 is a perspective view of another form of article supporting bracket which I may employ.

Referring to the drawings in detail, 1 designates a suitable base into which is set 35 a standard 2. This standard supports the main frame of the device, which, in the embodiment shown in the drawing, consists of a circular hoop 3. The ends of this hoop are set into a socket 4, into which also the upper 40 end of the standard 2 is screwed, such standard being provided with threads 2', as shown in Fig. 2. Also supported by the socket 4, and extending radially to approximately the center of the hoop 3 is a post or arm 5. 45 Other arms, such as indicated at 6, 7, and 8, may also be attached to the hoop 3 at any desired point thereof, and extend radially outward therefrom, such arms being shown in Fig. 1 as located 90 degrees apart. Each 50 of these arms is attached to the hoop 3 by means of a half round loop or clamp 9, secured to the arm and provided with a set screw 10 adapted to engage the frame. It will be seen, therefore, that by loosening 55 these set screws the corresponding arms may be adjusted to any desired position. It will

be particularly noted that such arms may all be turned inward, as shown in Fig. 2, so as to lie entirely within the circular frame 3 to facilitate packing the device for shipment. Also as illustrated in Fig. 2 the frame can be detached from the standard and base. This renders the device very compact and capable of being stored in a comparatively small space.

Various means of supporting on the arms 5, 6, 7 and 8, the articles to be displayed may be employed, in accordance with the nature of such articles. Where pointed articles, such as cutlery, are to be displayed, 60 the articles may be stuck into blocks of soft material, such as cork, as indicated at 13, and these blocks provided with openings adapted to be slipped over the arms. In Fig. 1 a knife 14 is illustrated as being supported in this manner.

When it is desired to display other articles they may be supported by means of hooks 12, carried by a bracket 11 supported at the end of an arm such as 6', as illustrated in 70 Fig. 4. Other methods of supporting the articles to be displayed may be employed without departing from the spirit of the invention.

In addition to the supporting arms above 75 described, I may, and preferably do, provide means for supporting a number of articles directly upon the frame 3 itself, at points between the arms. To this end I provide spring clips 15 which may be 80 readily attached to and detached from, the frame 3, and which may be secured thereto at any desired point. In Fig. 3 I have illustrated in detail one method in which such 85 clips can be constructed. Each clip comprises a fixed arm 16 and a movable arm 17 pivoted at 18 and preferably provided with a thumb piece 19 by means of which it may be manipulated. A spring 20 is provided 90 which normally urges the arm 17 toward the 95 position shown in the drawing. The clip above described is provided with a half round loop or clamp 21 adapted to encircle the frame 3, and carrying a set screw 22 by means of which it may be clamped in position. In Fig. 1 I have illustrated a pair of 100 scissors 23 as supported upon the frame by such a clip.

It will thus be seen that the essential feature of the invention, broadly considered, is 110 the provision of a circular or other closed frame, supported in a vertical plane, and

having means to support articles to be displayed at any desired point around such frame.

What I claim is:

- 5 A display stand comprising a base and standard rising therefrom, a closed hoop detachably secured to the top of said standard and disposed in a vertical plane, a supporting arm extending upwardly from said standard and in line therewith, and lying in the plane of the hoop, said arm being adapted to support articles inside the hoop, and a plurality of arms carried by said hoop and

adjustable circumferentially thereon, said arms when in operative position extending 15 radially outward from said hoop but being rotatably mounted thereon, whereby they may be turned so as to extend radially inward.

In testimony whereof I have affixed my 20 signature, in presence of two witnesses.

PERCY LIONEL DAVIS.
